HANS M. ERDMANN, OF NEW YORK, N. Y., ASSIGNOR TO NE-ARGA CORPORATION, OF NEW YORK, N. Y., A CORPORATION OF NEW YORK

LAMP STARTING DEVICE

Application filed January 18, 1930. Serial No. 421,678.

This invention relates to starting devices for mercury arc lamps and similar apparatus.

It is an object of my invention to provide a starting means for mercury arc lamps or similar electrical discharge devices, which is so arranged as to start operation of the lamp and then remain ineffective until it is intentionally made effective again.

In the production of talking moving pictures it is important to have, as nearly as possible, a complete absence of all unnecessary noises and electrical disturbances. Mercury arc lamps equipped with starting devices of the type heretofore known are unsuitable for use in the production of talking pictures because when one of the lamps becomes extinguished, the starting device thereof immediately starts to function so as to reignite the lamp, thereby producing a clicking noise. The noise produced by the ordinary starting device is sufficient to cause a serious disturbance, which will be made part of the sound record. Likewise, when the starting device serves to create a momentary high potential starting current, this starting current causes a disturbance in the recording of the sound if an electrical process is being used. This recording is usually carried out by electrical recording apparatus, including a high power amplifier which serves to amplify the sound currents picked up through microphones. These amplifiers are sufficiently powerful to pick up the disturbing electrical waves as well, thereby impressing on the recording medium an undesired noise.

In accordance with my invention I provide means responsive to the initiation of operation of the lamp to render inactive the starting mechanism thereof so that if the lamp later becomes extinguished, the starting device will be unable to function. The lamp will therefore remain unlit until it is manually restored to operation at an opportune moment. I accomplish this result by providing relay means which serves to open the energizing circuit of the starting device upon the creation of a self-sustained discharge through the tube.

The objects and advantages of my inven-

tion and the manner of attaining them will be made clear in the following description and accompanying drawing.

In the drawing, reference numeral 1 indicates a mercury arc tube or other similar electrical discharge device requiring a high starting potential, which is supplied with current from a source of power 2 by means of conductors 3 and 4. Connected in series with the tube is an inductance 5 and a control switch 6. When the switch 6 is closed to initiate operation of the tube, a current passes through the conductor 3, ballast resistance 11, contacts 9 of switch 8, conductor 4 and inductance 5, thereby magnetizing core 16. Upon magnetization of the core, tiltable armature 7 is attracted thereto, thereby tilting mercury switch 8 and opening contacts 9 thereof. This causes a breakage in the circuit of the inductance 5, producing a high potential surge which supplies the necessary high potential for creating a discharge through the tube 1. The inertia of the armature 7 in tilting under the attracting force of the core 16 is sufficient to cause the globule of mercury within the switch 8 to close the circuit between contacts 10, thereby causing an auxiliary current to flow from the conductor 3 through the ballast resistances 11 and 12 and holding coil 13, to the other side of the line. The coil 13 is preferably made of a large number of turns of fine wire so as to draw but a small amount of current. The amount of current may further be limited by proper selection of the value of resistances 11 and 12. The tube 1 is now in operation and even if it should later be extinguished for some reason, such as a slight drop in line potential or blast of cold air, the starting mechanism will be unable to repeat the starting operation because the contacts 9 are maintained open by the action of holding coil 13, which keeps the armature 7 tipped against the core 16. To render the starting device again operative, it is necessary momentarily to open the switch 6, thereby deenergizing the holding coil 13 and permitting the armature 7 to rotate to its original position under the influence of spring 14. Should the tube 1 not start on the first closure of the switch 6

because of the fact that the surge of potential produced by the inductance 5 is not sufficient, the switch may be opened and closed again, whereupon another surge will be created.

5. While I have shown a mercury type switch at 8, it will be understood that any other type may be used if desired, it merely being necessary that the armature 7, in moving towards the core 16, break a pair of contacts at 9 and 10 close a pair of contacts at 10. Likewise, the coil 13 may be dispensed with and a portion or all of the inductance 5 utilized to hold the armature 7 in tilted position. In this case the wire 15 will be connected either at some intermediate point of the coil 5 or else on the load side thereof. I prefer, however, to utilize the holding coil 13, as shown, because such an arrangement results in a smaller current consumption than the alternative form just mentioned. The function of condenser 17 is to prevent arcing at contacts 9 thereby increasing the potential generated by inductance 5. In similar manner condenser 10 prevents formation of arcs at contacts 10.

25. It will be obvious to those skilled in the art that the invention is capable of a wide variety of modifications and adaptions, and that the present disclosure is intended merely to illustrate its nature without limiting its scope 30 which is defined in the claims.

What is claimed is:

1. In a lighting system, a lamp, a power source therefor, an inductance in series with said lamp, a circuit shunted directly across the terminals of said lamp, switching means responsive to energization of said inductance for opening said circuit and simultaneously closing a circuit through holding means for maintaining said switching means in operated 40 position so that said circuit remains open.

2. In a lighting system, a lamp, a power source therefor, a starting device for creating a high potential for starting said lamp, a control switch actuating said starting device, and 45 magnetic means for operating said control switch to create a high starting potential and thereupon render said starting device ineffective until after said control switch is opened.

50. 3. In a lighting system, a gaseous discharge lamp, a power source and a control switch therefor, a starting inductance in series with said lamp, a circuit for energizing said inductance independently of said lamp, 55 a switch in said circuit, means responsive to closure of said control switch for opening said switch, and means responsive to operation of said means first mentioned for holding said circuit open.

60. 4. In a control circuit for an electrical discharge tube requiring a high starting potential, a source of power, and a starting means for said device, said means comprising an inductance in series with said tube, a pair of contacts in shunt with said tube, means re-

sponsive to the energization of said inductance by closure of the line switch for breaking said contacts and closing an auxiliary shunt circuit through a holding coil to maintain said contacts open.

5. A device in accordance with claim 3 wherein the means second mentioned is of high resistance.

In testimony whereof, I have signed my name to this specification, this 16th day of January, 1930.
